(57) **CLAIM**

The ornamental design for a display screen or portion thereof with an animated graphical user interface, as shown and described.

DESCRIPTION

FIG. 1 is a front view of a display screen or portion thereof with an animated graphical user interface showing a first image in a sequence of one embodiment showing our new design;

FIG. 2 is a second image thereof;

FIG. 3 is a third image thereof;

FIG. 4 is a front view of a display screen or portion thereof with an animated graphical user interface showing a first image in a sequence of a second embodiment showing our new design;

FIG. 5 is a second image thereof;

FIG. 6 is a third image thereof;

FIG. 7 is a front view of a display screen or portion thereof with an animated graphical user interface showing a first image in a sequence of a third embodiment showing our new design;

FIG. 8 is a second image thereof;

FIG. 9 is a third image thereof;

FIG. 10 is a fourth image thereof;

FIG. 11 is a fifth image thereof;

FIG. 12 is a sixth image thereof; and,

FIG. 13 is a seventh image thereof.

FIGS. 1-6 show break-away symbols in broken lines that indicate the appearance of any portion of the article between the break lines forms no part of the design.

The broken lines in the Figures show portions of a display screen or portion thereof with animated graphical user interface and form no part of the claimed design.

The appearance of the animated images sequentially transitions between the images shown in FIGS. 1-3. The appearance of the animated images sequentially transitions between the images shown in FIGS. 4-6. The appearance of the animated images sequentially transitions between the

(Continued)

images shown in FIGS. 7-13. The process or period in which one image transitions to another image forms no part of the claimed design.
